HIGH TENSION FUSE SWITCH

Thomas E. Murray, Jr., Brooklyn, N. Y., assignor
to Metropolitan Device Corporation, a corpora-
tion of New York

Application February 5, 1930, Serial No. 425,949

8 Claims. (Cl. 200—114)

This invention relates to a fused switch and more particularly to a fuse and switch for high tension electric circuits.

An object of the invention is to provide an apparatus in which the blowing of the fuse serves automatically to disconnect the fuse from the circuit.

Other objects of the invention are to provide a fuse and switch circuit in which the switch connecting the fuse to the circuit is opened immediately after or substantially simultaneously with the blowing of the fuse and in which the fuse may be readily replaced after blowing without changing the position of the switch.

With these and other objects in view, which will appear in the following description, the invention comprises the apparatus and circuit described in the following specification and claims.

The various features of the invention are illustrated in the accompanying drawing, which shows a vertical sectional view of a fused switch embodying a preferred form of the invention. In my invention the blowing of a confined fuse serves to open a switch interposed between the fuse and the lead wire or wires and thereby to disconnect the fuse from the line wires. The switch is so arranged and constructed that, once opened in this manner, it remains open until manually closed. The fuse may therefore be removed and replaced without the necessity of first manually disconnecting its terminals from the circuit, thus insuring against injury through an inadvertent failure to take this precaution. Preferably two switches are employed with each fuse, one for each fuse terminal so that the fuse terminals are entirely disconnected from all parts of the circuit when it has blown.

Referring more particularly to the accompanying drawing, the fuse 1 and a pair of knife switches 2 and 3 are contained within an insulating housing or container 4 and are mounted therein on a barrier or wall 5 having a flat, substantially horizontal, supporting table or plate 6, on which the fuse is supported, and a pair of side plates 7 and 8 depending vertically or at right angles from opposite edges of the table 6 and carrying the switches 2 and 3, respectively.

Each of the switches 2 and 3 has a terminal bracket 9 connected through a wire 10 to its respective circuit terminal 11. Pivotaly mounted on the brackets 9 are switch blades 12 and 13, respectively, for the two switches, the blades 12 and 13 being of a length to project upwardly a short distance above the surface of the plate 6 and to swing from vertical position outwardly

and downwardly in opposite directions from the plates 7 and 8. When in their vertical positions the switch blades 12 and 13 connect the brackets 9 to contact clips 14 and 15, respectively.

The fuse 1 comprises a fusible strip 16 connected at its ends to the clips 14 and 15 and extending through a pair of closely spaced plugs 17 and 18 slidably mounted in an insulating cylinder 19. The fusible strip 16 is notched or constricted as at 20, between the plugs 17 and 18 and the cylinder 19 projects a substantial distance beyond the edges of the plugs, so that, upon an overload of the circuit, the fuse wire blows at 20 generating sufficient pressure to propel the plugs in opposite directions through the open ends 15 of the cylinder 19. The cylinder 19 is aligned between the upper ends of the switch blades 12 and 13, so that as the plugs 17 and 18 are propelled from the cylinder they strike the switch blades and throw them outwardly to open positions. The fuse is thus disconnected from the terminals 11 and may be removed or replaced and the switch blades 12 and 13 closed and the fuse connected into the circuit.

To deflect the propelled plugs downwardly into the container 4 a pair of deflectors 21 and 22 are mounted at the upper edges of opposite walls of the container and are reinforced with braces 23 and 24.

Although the use of two switches is preferable the fuse may be arranged to operate but a single switch blade one of the plugs 17 or 18 being fixed in position or replaced by a fixed wall or barrier.

Various modifications may be made by those skilled in the art without departing from the invention as defined in the appended claims:—

What I claim is:

1. Apparatus of the type described comprising a switch movable to open position, a fuse in series with said switch, and a member driven by 40 said fuse upon blowing to move said switch to open position.

2. Apparatus of the type described which comprises a confined fuse, a plug movable by the blowing of said fuse, and a switch in series with 45 said fuse positioned to be driven to open position from the movement of said plug.

3. Apparatus of the type described which comprises a confining fuse, a plug movable by the blowing of said fuse, and a knife switch in series 50 with said fuse positioned to be driven to open position by the movement of said plug upon the blowing of said fuse.

4. An electric circuit comprising a confined fuse, a pair of plugs movable by the blowing of 55

said fuse and a pair of switches in series with said line positioned to be opened by the movement of said plugs upon the blowing of said fuse.

5. An electric circuit comprising a fuse, a cylinder enclosing fuse, a plug confining said fuse in said cylinder, a knife switch in series with said fuse having a blade in the path of said plug and movable to open position by projection of plug out of cylinder.
- 10 6. An electric circuit comprising a container, a barrier in said container, a pair of switches having projecting knife blades, a fuse connected in said circuit between said switches, a cylinder enclosing said fuse and aligned with the projecting parts of said switch blades and plugs in said cylinder confining a part of said fuse and slidably to project against said switch blades.
- 15

7. An electric circuit having a supply main, a fuse, and a switch between said supply main and said fuse in series therewith, and a member driven by the blowing of said fuse to move said switch to open position.

- 5
8. In a circuit opening device, for an electric circuit the combination with a pair of contact members, of a blade movable to open and close a circuit between said pair of contact members, and means operable upon the passage of an excess current through said switch for moving said blade to open said circuit, said means comprising a projectile normally spaced from said blade and arranged to strike against said blade to move said blade to open position.
